Issue, Dec. 5, 1872.

UNITED STATES PATENT OFFICE.

LUTHER W. HARWOOD, OF TROY, NEW YORK, ASSIGNOR TO FULLER, WARREN & CO., OF SAME PLACE.

DESIGN FOR A COOKING-STOVE.

Specification forming part of Design No. 6,284, dated December 10, 1872.

To all whom it may concern:

Be it known that I, LUTHER W. HARWOOD, of the city of Troy, in the county of Rensselaer and State of New York, have invented and produced a new and original Design for Cooking-Stoves, of which the following is a specification, reference being had to the accompanying wood-cut or engraving of a stove which embodies my said design.

One part of my invention consists of the design for the combined foot and leg, as distinguished by the representation of a lace-up shoe, *a*, on the foot, and a fluted covering, *b*, with the pointed border *c* on the upper portion of the leg, all shaped and arranged so as to appear as represented in the aforesaid wood-cut. Another part consists of the pendent ornament *d*, shaped and arranged on a plate or door of a stove so as to appear substantially as shown in the aforesaid cut. Another part consists of the circular ornamented molding *e* or *f*, shaped and arranged on a door or plate of a stove so as to appear as represented in the cut. Another part consists of the circle of beads *g*, arranged around the denominational figure on the side plate of a stove as shown in the accompanying engraving. Another part consists of the combination of the ornamental moldings *h* and *i*, shaped and arranged together on a door or panel of a stove substantially as represented in the engraving. Another part consists of the combination of the pendent ornament *d* and ornamented mold-

ing *h*, shaped and arranged substantially as represented in the aforesaid cut or engraving, with or without one or more of the circular moldings *e* or *f* and ornamental border-moldings *i* *j*. Another part consists of the ornamental design for the inclined part *k* of the hearth, as distinguished by the word "Casket," composed of letters shaped and arranged so as to present the ornamental appearance represented in the aforesaid engraving.

I do not claim the word "Casket" as a trademark.

What I claim as my invention is—

1. The design for the combined foot and leg, as herein specified.
2. The pendent ornament *d*, shaped and arranged on a plate, door, or panel of a stove, as set forth.
3. The circular bead-ornamented molding *e* or *f*, shaped and arranged on a door or panel of a stove, as described.
4. The circle of beads *g*, arranged on a stove around its denominational figure, as described.
5. The combination of the ornamental moldings *h* and *i*, as set forth.
6. The combination of the pendent ornament *d* and ornamental molding *h*, as set forth.
7. The ornamental design for the inclined part *k* of the hearth, as herein set forth.

LUTHER W. HARWOOD.
